UNITED STATES PATENT OFFICE.

ROBERT L. RADFORD, OF ASHEVILLE, NORTH CAROLINA, ASSIGNOR OF ONE-FOURTH
TO PHILIP R. MOALE, OF ASHEVILLE, NORTH CAROLINA.

PACKAGE-TYING DEVICE.

1,271,767.

Specification of Letters Patent. Patented July 9, 1918.

Application filed August 17, 1917. Serial No. 186,799.

To all whom it may concern:

Be it known that I, ROBERT L. RADFORD, a citizen of the United States, residing at Asheville, in the county of Buncombe and 5 State of North Carolina, have invented new and useful Improvements in Package-Tying Devices, of which the following is a specification.

This invention relates to a package tying device which is intended to be used by postal clerks when forming packages of letters and the like, although the construction of the tie is such that it may be advantageously employed in retaining other articles in pack- 10 age form when found desirable.

The primary object of the invention is to provide a package tie of this character having improved means of novel construction for retaining a length of cord wound 15 about the package and with the means so constructed as to positively prevent the portions of the cord engaged therewith from becoming chafed or cut.

With these and other objects in view, the 20 invention resides in the novel combination and arrangement of parts, which will be hereinafter described and particularly pointed out in the claim.

The preferred embodiment of the invention 25 has been illustrated in the accompanying drawings, although no restriction is necessarily made to the precise details of construction therein shown, as changes, alterations, and modifications within the scope 30 of the claim may be resorted to when desired.

In the drawings:—

Figure 1 is a view showing the improved tie applied to a package.

40 Fig. 2 is a section on the line 2—2 of Fig. 1.

Fig. 3 is a detail perspective view of the cord clamp holder.

Fig. 4 is a plan view of one of the blanks 45 from which the cord clamps are formed.

Fig. 5 is a view of a slightly modified form of a cord clamp holder.

Fig. 6 is a view of the portion of the cord clamp holder showing a modified form 50 of cord clamp mounted thereon.

Like characters of reference denote corresponding parts throughout the several views in the drawing.

Referring now to the drawing in detail 55 the letter A designates a package to which

is shown applied the improved tie B. The tie B includes a cord clasp holder 10 which in the preferred form of the invention is in the form of a double billed hook formed from a single length of resilient material, 60 such as wire or the like which is flattened upon opposite sides for a portion of its length. The flattened portions of the rod are folded upon themselves to provide the oppositely extending and inclined bills 11 65 of the hook, the flattened portions of the wire being so folded that the bills 11 lie upon opposite sides of the shank 12 of the hook and with the flat faces on the bills and the shank confronting each other. 70

A pair of V-shaped cord clasps 13 which are formed from a blank of suitable material 14 are mounted to slide on the shank and bills of the hook which constitutes a cord clasp holder. Each clasp 13 comprises 75 a pair of connected and oppositely inclined arms 15 which are arranged between the shank and a bill on the hook and engage the flat faces thereon. The arms 15 which are employed to grip a cord 16 adjacent its 80 ends when wound about a package B, are provided adjacent their free ends with extensions which are bent to form collars 17 through which the shank of the hook and a bill thereon are passed, thus enabling the 85 cord clasps to be slidably retained on the hook. The flattened faces on the rod from which the cord clasp holder is formed provide shoulders 18 between the ends of the shank of the hook which serve to limit the 90 sliding movement of the cord clasps in one direction. 95

To apply a package tie as disclosed in the preferred form of the invention to a package a length of cord 16 is looped adjacent one end thereof and the portion passed between the arms 15 of one of the cord clamps and the cord clamp drawn toward the end of the cord clasp holder upon which the clasp is mounted, such sliding movement 100 of the cord clasp on the cord clasp holder forcing the arms of the cord clasp toward each other and into firm engagement with the cord 16. The cord clasp holder is now placed upon the package and the cord wound thereabout and engaged between the arms of the other cord clasp 13, which is then moved by pulling upon the cord toward the end of the cord clasp holder upon which the cord 105 clasp is mounted so that the arms on the 110

last-mentioned cord clasp will be moved toward each other for firmly gripping the portion of the cord passing therebetween.

When it is desired to remove the package tie from the package an end of the cord 16 is grasped and pulled to move the cord clasp engaged therewith toward the central portion of the cord grasp holder, such movement of the cord clasp allowing the arms 10 thereof to be spread apart and release their grip upon the cord, so that the cord may be freed from the clamp and unwound from the package.

When it is desired that the cord 16 becomes a permanent part of the package tie I provide the cord clasp holder disclosed in Fig. 5 in the drawing as in the form of a single bill hook upon which is mounted the cord clasp 13 constructed as disclosed in the 20 preferred form of the invention. In the modified form of cord clasp holder the shank of the hook is bent to form an eye 20 to which an end of the cord 16 may be attached.

25 The modified form of cord clasp holder disclosed in Fig. 6 in the drawing is identical in construction with that shown in the preferred form of the invention with the exception that the arms 15 have formed

thereon transversely extending corruga- 30 tions 21 which insure the arms obtaining a firm grip upon the cord 16. The modified form of cord clasp may be employed in connection with either form of cord clasp holder disclosed in the drawing. 35

From the foregoing description taken in connection with the accompanying drawing it is apparent that a package tie has been provided wherein a plurality of cord clasps are mounted upon a cord clasp holder 40 so constructed that a cord engaged with the clasp may be held wound about a package without knotting the ends of the cord and without likelihood of the cord becoming chafed or injured in its engagement with 45 the clasps.

Having thus described the invention, what is claimed as new, is:—

In a package tie, a hook having oppositely extending and inclined bills at opposite ends of its shank, V-shaped cord clamps interposed between said shank and bills, collars on said clamps through which said shank and bills are passed, and shoulders on said shanks adjacent the free ends of 50 55 said bills.

In testimony whereof I affix my signature.
ROBERT L. RADFORD.
